BARREL STAVE SETTING-UP MACHINE

Walter F. Newhouse, Benton Harbor, Mich.

Application June 8, 1931. Serial No. 542,767

14 Claims. (Cl. 147—3)

This invention relates to machinery for use in setting up barrel staves, in order to assemble the staves in barrel form, preliminary to the fastening of the hoops and the bottom head in place.

Generally stated, the object of the invention is to provide a novel construction and arrangement whereby the barrel staves can be assembled with their lower end portions in tight engagement with each other, within a truss ring or truss hoop, and whereby the upper end portions of the staves can then be bent inwardly and brought tightly together at their edges, preliminary to then placing a temporary hoop or ring over the upper portions of the staves, whereby the barrel-stave assembly can then be lifted out and transferred to machinery for applying the hoops of the barrel, or for securing one head in place.

It is also an object to provide certain details and features of construction and combinations tending to increase the general efficiency and the desirability of a barrel-stave setting-up machine of this particular character.

To the foregoing and other useful ends, the invention consists in the matters hereinafter set forth and claimed, and shown in the accompanying drawings; in which—

Fig. 1 is a plan view of a barrel-stave setting-up machine involving the principles of the invention, showing the various elements of the machine in position to receive the loose staves.

Fig. 2 is an enlarged detail or fragmentary view.

Fig. 3 is a section on line 3—3 in Fig. 2 of the drawings.

Fig. 4 is a side elevation of the machine shown in Fig. 1 of the drawings, showing the barrel staves inserted and ready to be drawn together at their upper ends.

Fig. 5 is a plan view of one of the barrel staves.

Fig. 6 is a view similar to Fig. 4, showing the machine as having been operated to draw the upper ends of the barrel staves together.

Fig. 7 is a perspective of one of the complete barrel-stave assemblies, held together with temporary rings or truss hoops, removed from the said machine.

Fig. 8 is a vertical section on line 8—8 in Fig. 1 of the drawings, showing the staves in the condition in which they are shown in Fig. 4 of the drawings.

Fig. 9 is a sectional view showing another form of the invention.

Fig. 10 is a view looking down on the stave contracting mechanism, with the parts as shown in Fig. 6 of the drawings.

Fig. 11 is an enlarged detail section on line 11—11 in Fig. 10 of the drawings.

Fig. 12 is an enlarged detail section on line 12—12 in Fig. 10 of the drawings.

As thus illustrated, the invention comprises a suitable base 1 having an upright portion 2 at the rear thereof, the upper ring frame 3 being secured to the upper portion of the upright 2 by means of bolts or screws 4, or in any suitable or desired manner. An upright brace 5 is interposed between the front portion of the ring frame 3 and the front portion of the base 1, in the manner shown, whereby the ring frame 3 is firmly supported in horizontal position. A disk-like form plate 6 is secured upon the base 1 by a center screw or bolt 7, in the manner shown.

A metal band 8 is secured to the bracket 9 at 10, pivotally, and is provided with a toggle joint 11 which is operated by a foot pedal 12, whereby the band 8 may be contracted or expanded at will. A spring 13 is connected to the foot pedal 12 and serves normally to raise this pedal, thereby to keep the band 8 in normally expanded position.

The stave clamping or embracing arms 14 are pivoted at 15 on brackets 16 that are secured to the ring frame 3 in any suitable manner. Each pin 15 extends through the bracket 16 and through a portion of the ring 3 below, and the adjacent portion of the arm 14 is between the bracket 16 above and the projecting portion of the ring 3 below, so that the pin 15 has upper and lower bearings between which the arm 14 is held by the pin. A ring 17 is loosely mounted on the top of the ring frame 3 in such a manner that the ring 17 can rotate or oscillate slightly, about the vertical axis of the machine, and this ring 17 is connected by links 18 with the arms 14, whereby oscillation of the ring 17 will cause said arms to move in a horizontal plane, causing said arms to move toward and away from the central vertical axis of the machine. To cause this oscillation of the ring 17, and to thereby cause the operation of the said arms 14, a hand lever 19 is pivoted on the stationary frame at 20, as shown more clearly in Figs. 4 and 6 of the drawings.

A casting 21 is secured to the ring 17, as shown, and this casting is connected by a link 22 to the hand lever 19, whereby operation of this lever will cause a partial rotation or oscillation of the ring 17, in the desired manner.

In the assembly of the staves 23, in the manner shown in the drawings, a temporary ring or truss hoop 24 is desirably employed, this ring being removably seated on brackets 25 provided on

the base in the manner shown. Rock shafts 26 are provided at the front and rear of the machine, in bearings mounted on the base, and these rock shafts are connected together by cranks 27 on the ends thereof, and by a link or bar 28 pivoted on said cranks. The front shaft 26 is provided with a foot pedal 29, and by depressing this foot pedal both shafts 26 will be rocked in the desired manner. The arms 30 are rigid with the shafts 26, and are disposed in position to engage the under side of the truss hoop 24, when the foot pedal 29 is depressed, thereby to raise the barrel assembly out of engagement with the base of the machine, and out of engagement with the form plate 6, after the assembly is complete.

After the hand lever 19 is thrown into the position shown in Fig. 6 of the drawings, so as to contract the arms 14 and cause them to bring the upper ends of the staves together, a truss hoop 31 is then slipped over the ends of the staves, to hold them in contracted position. Preliminary to this, the pedal 12 is depressed to contract the staves by means of the band 8, thereby holding the lower portions of the staves in tight engagement with each other, preliminary to the bending of the upper ends of the staves inwardly to receive the truss hoop 31 previously mentioned. The band 8 is contracted or tensioned around the staves to prevent the vertical edges of said staves from slipping past each other, during the time the contracting arms 14 are causing the upper ends of the staves to be drawn together. This slipping condition is more liable to occur when badly warped and crooked staves are assembled. In this connection, it will be seen that the band 8 has guide portions 32 that engage the stationary guides 33, whereby the front portion of the band is movably supported in horizontal position, but is free to flex and operate in the desired manner.

When the barrel assembly is complete, the foot pedal 29 is depressed, as stated, and the arms 30 raise the barrel assembly out of engagement with the form plate 6, it being observed in this connection that a spring 34 is applied to the rear shaft 26 in a manner to yieldingly hold the pedal 29 in raised position, so that the arms 30 will be normally depressed.

In Fig. 9, a wire hoop 35 is shown, in place of the truss hoop 24 previously mentioned, also, the bottom form plate 36 is raised a distance from the base, being removably secured in place by the center screw or bolt 37, as shown.

The arms 14 are long enough to be overlapping, as shown, whereby these arms circumscribe the upper portions of the barrel staves, and when operated serve in effect to form a continuously contacting ring around the upper portion of the barrel-stave assembly, whereby each and every stave is bent inwardly at its upper end, in such a manner that the upper truss hoop 31 can then easily be slipped over the barrel staves. When the work is done, a barrel-stave assembly of the kind shown in Fig. 7 is produced, and this assembly is then ready to be placed in a stapling machine, for example, for the stapling of the hoops thereto, or for the fastening of one of the heads into the end of the barrel. This is the preferred method, but it will be understood that the hoops or rings need not necessarily be temporary hoops, but may be wood hoops or wire hoops, or other hoops, to be stapled or otherwise permanently fastened to the barrel staves, to become a part of the ultimate barrel.

Fig. 7 shows the preliminary barrel-stave set-

up, in its preferred form, and it will be understood, of course, that, before being transferred to the stapling machine, for stapling the hoops in place, this assembly may be operated upon or treated in any desired manner for the reception of the barrel heads. In fact, the barrel-stave assembly shown and described may be preliminary to any subsequent operation thereon, so far as the broader aspects of the invention are concerned, but the machine shown and described is especially adapted for the setting-up and formation of a barrel-stave assembly which can thereafter be transferred to other machinery for advantageously completing the work of forming the assembly into a suitable barrel which is open at one end thereof to receive the load, and which can thereafter be closed in any suitable or desired manner.

Looking at Fig. 10 of the drawings, it will be seen that fixed vertical axes 15 are spaced apart on the circumference of a circle struck from the vertical axis of the barrel. It will also be seen that the movable pivots of the links 18, on the ring 17, are spaced apart on the circumference of a larger circle also struck from said central vertical axis. With this arrangement, the arms or levers 14 have engagement with the barrel at points between their ends and the pivots of the links 18 on said arms. This gives the arms 14 the desired character of movement, advantageously, and provides a clear space in the center of the machine, for the barrel, the links 18 being interposed between the outer edges of the arms 14 and the ring 17, in the manner shown. Thus, when the arms or levers 14 are tightened around the barrel, the curved inner edges of these arms, as shown in Fig. 10, provide practically a complete circular engagement with the barrel, so that practically all barrel staves are engaged and forced into the line of a circle, so that the upper ring 31 can be slipped over the top portion of the barrel. In this way, a hand machine is provided for assembling barrel staves, which is quite easy and fast to operate.

It will be seen that the links 18 are in effect toggle-joint links, and exert an inward toggle pushing action when the ring 17 is partially rotated in the direction shown in Fig. 10 of the drawings. This is because the pivots 38 of said links, on the ring 17, form toggle-joints, in effect, whereby when the ring 17 is rotated in the direction shown in Fig. 10 of the drawings, these toggle links 18 endeavor, so to speak, to become radial to the vertical axis of the barrel, and in so doing exert a powerful toggle action to push the arms 14 inwardly against the barrel. During such toggle action, the ring 17 in effect forms the other link of the toggle-joint, but instead of having a swinging action about an axis, the cooperating portion of the ring slides against the flange 3 on the outside ring. Or, stated another way, the toggle-joint 38 swings a distance about the vertical axis of the barrel, and the result is that the links 18 have a true toggle pushing action, a very powerful one, when the ring 17 is rotated in the direction shown in Fig. 10 of the drawings. Thereafter, when the ring 17 is rotated in the reverse direction, the action of the links 18 is a pulling action, but at this time very little power is needed to swing the arms 14 outwardly to release the barrel. Thus the instrumentalities for contracting the upper ends of the barrel staves is very powerful, and very easily operated, and provide practically a continuous or unbroken circular contact with the outer sides of the barrel,

so that practically every stave is engaged and forced inwardly by the toggle action shown and described.

What I claim as my invention is:

- 5 1. A machine for assembling barrel staves in bilge barrel form, comprising positioning instrumentalities for receiving the lower end portions of the barrel staves with their side edges in engagement with each other, with an annular member 10 encircling the lower portions of the staves, and barrel-stave contracting instrumentalities arranged above, shaped to form practically a complete circular engagement with the top portion of the barrel, rotatively operative about a fixed vertical axis to contract the upper ends of the staves and bend them inwardly to receive another annular member to encircle the upper portions of the staves, which axis is the vertical axis of the barrel, said contracting instrumentalities having 20 fixed vertical axes spaced apart on the circumference of a circle struck from said barrel axis, with movable vertical axes forming toggle-joints spaced apart on the circumference of a larger circle struck from said barrel axis, and being operative about all of said axes by simultaneous movement of said toggle-joints on said larger circle to exert a toggle thrust inwardly and thereby contract the upper ends of the staves, and thereafter by reverse motion of said joints to disengage the barrel assembly held together by said lower annular member and said upper annular member. 25
2. A bilge barrel stave assembly machine, as specified in claim 1, in combination with contracting means disposed a distance above said positioning instrumentalities, below said contracting instrumentalities.
3. A bilge barrel stave assembly machine, as specified in claim 1, in combination with contracting means disposed a distance above said positioning instrumentalities, below said contracting instrumentalities, said contracting means comprising a flexible band provided with a toggle-joint, and provided with a foot pedal for operating said toggle-joint. 40
4. A bilge barrel stave assembly machine, as specified in claim 1, said positioning instrumentalities comprising a bottom form plate having a circular edge concentric to but of less diameter than said circles for engaging the lower ends of the staves a distance below said lower annular member. 50
5. A bilge barrel stave assembly machine, as specified in claim 1, said contracting instrumentalities comprising a plurality of pivoted arms operable in a horizontal plane about the fixed axes on said first-mentioned circle for engaging the outer sides of the staves, and comprising means operative about said movable axes on the larger circle for simultaneously operating said arms to force the staves inwardly, and for pulling the arms outwardly to release the barrel-stave assembly. 60
6. A bilge barrel stave assembly machine, as specified in claim 1, said barrel-stave contracting instrumentalities comprising a plurality of pivoted arms operable in a horizontal plane, said arms having stationary pivotal mountings, a ring oscillatory in a horizontal plane, links connecting said ring with intermediate portions of said arms, with the portions of the arms between their ends and said links formed to engage the barrel staves, and means including a hand lever 70 for oscillating said ring. 75
7. A bilge barrel stave assembly machine, as specified in claim 1, comprising foot-operated rock shafts each having arms for engaging said lower annular member to raise the finished barrel-stave assembly in said machine. 80
8. A bilge barrel stave assembly machine, as specified in claim 1, comprising front and rear lifting means for raising the finished barrel-stave assembly in the machine, to facilitate removal of the assembly upwardly from the machine. 85
9. A bilge barrel stave assembly machine, as specified in claim 1, comprising barrel-stave contracting means disposed a distance below said contracting instrumentalities, said stave contracting means comprising a flexible band, with means for contracting the band around the staves, a hinge for the rear portion of the band, and guides for the front portion of the band, whereby the band is supported in horizontal position. 90
10. A bilge barrel stave assembly machine, as specified in claim 1, comprising barrel-stave contracting means disposed a distance below said contracting instrumentalities, said stave contracting means comprising a flexible band, with means for contracting the band around the staves, a horizontal hinge for the rear portion of the band, horizontal guides for the front portion of the band, co-operating with said guides to maintain the band in a horizontal plane. 105
11. A bilge barrel stave assembly machine, as specified in claim 1, said positioning instrumentalities comprising a removable rotary disk disposed in a horizontal plane, of less diameter than said circles, having its annular edge formed to disengageably engage the lower ends of the staves, a stationary base supporting the lower ends of the staves, said disk being provided at its center with a fastening device, forming a pivot on said base, coincident with said barrel axis, 110 whereby the disk can be removed at will. 115
12. A barrel-stave setting-up machine comprising positioning instrumentalities for receiving the lower end portions of the barrel staves with their side edges in engagement with each other, and with an annular member encircling the lower portions of the staves, and barrel-stave contracting instrumentalities arranged above, shaped to form practically a complete circular engagement with the barrel, rotatively operative about a fixed vertical axis to contract the upper portions of the staves and bend them inwardly, thereby to receive another annular member to encircle the upper portions of the staves, which axis is the vertical axis of the barrel, said last-mentioned instrumentalities having fixed vertical axes spaced apart on the circumference of a circle struck from said barrel axis, with movable vertical axes spaced apart on the circumference of a larger circle struck from said barrel axis, being operative about all of said axes to disengage the barrel assembly held together by said lower annular member and said upper annular member, in combination with barrel-stave contracting means disposed a distance above said positioning instrumentalities, below said other contracting instrumentalities, said second-mentioned barrel-stave contracting means comprising a flexible band provided with a toggle-joint, and provided with a foot pedal 120 for operating said toggle-joint. 125
13. A barrel-stave setting-up machine comprising positioning instrumentalities for receiving the lower end portions of the barrel staves with their side edges in engagement with each 130
- 135
- 140
- 145
- 150

other, and with an annular member encircling the lower portions of the staves, and barrel-stave contracting instrumentalities arranged above, shaped to form practically a complete circular engagement with the barrel, rotatively operative about a fixed vertical axis to contract the upper portions of the staves and bend them inwardly, thereby to receive another annular member to encircle the upper portions of the staves, which axis is the vertical axis of the barrel, said last-mentioned instrumentalities having fixed vertical axes spaced apart on the circumference of a circle struck from said barrel axis, with movable vertical axes spaced apart on the circumference of a larger circle struck from said barrel axis, being operative about all of said axes to disengage the barrel assembly held together by said lower annular member and said upper annular member, said machine also comprising foot-operated rock shafts each having arms for engaging said lower annular member to raise the finished barrel-stave assembly in said machine.

14. A barrel-stave setting-up machine comprising positioning instrumentalities for receiving the lower end portions of the barrel staves

with their side edges in engagement with each other, and with an annular member encircling the lower portions of the staves, and barrel-stave contracting instrumentalities arranged above, shaped to form practically a complete circular engagement with the barrel, rotatively operative about a fixed vertical axis to contract the upper portions of the staves and bend them inwardly, thereby to receive another annular member to encircle the upper portions of the staves, which axis is the vertical axis of the barrel, said last-mentioned instrumentalities having fixed vertical axes spaced apart on the circumference of a circle struck from said barrel axis, with movable vertical axes spaced apart on the circumference of a larger circle struck from said barrel axis, being operative about all of said axes to disengage the barrel assembly held together by said lower annular member and said upper annular member, said machine also comprising front and rear lifting means for raising the finished barrel-stave assembly in the machine, to facilitate removal of the assembly upwardly from the machine.
